A. N. LONGFIELD ET AL.

VENTILATING DEVICE

Filed Sept. 5. 1925

Flj. 1

8 Fig. 2 4

Fig. 3

Fig. 5

A diagram of a double-paned window frame. The frame is divided into four quadrants by a central crossbar. The top-left quadrant is labeled '6' and has a diagonal hatching pattern. The top-right quadrant is labeled '5'. The bottom-left quadrant is labeled '7' and has a diagonal hatching pattern. The bottom-right quadrant is labeled '14'. The left edge of the frame is labeled '13'. The right edge of the frame is labeled '1'. The bottom edge of the frame is labeled '15'. The central crossbar is labeled '8' on its left side and '9' on its right side. The bottom-most part of the frame is labeled '4' on its left side and '10' on its right side. The entire frame is set against a background with the letters 'A' and 'B' visible on the right.

UNITED STATES PATENT OFFICE.

ARCHIBALD N. LONGFIELD AND BERTHA I. LONGFIELD, OF ST. PAUL, MINNESOTA.

VENTILATING DEVICE.

Application filed September 5, 1925. Serial No. 54,636.

This invention pertains to improvements in ventilating devices, and its object is to provide a ventilator for closed vehicles of various kinds and other housings where a current of air passes on the outside.

Another object is to provide a ventilator having reversible vanes which will automatically adjust themselves to the direction of the air currents and which can be governed 10 as desired.

These and other objects will be apparent from the accompanying drawing and specification.

In the drawing:

15 Figure 1 is a horizontal section of a removable ventilator designed in accordance with our invention;

Figures 2 and 3 are side elevations of the ventilator;

20 Figure 4 is a cross-section of the ventilator removably mounted;

Figure 5 is a cross-section of a built-in ventilator designed in accordance with our invention.

25 In carrying out this invention, we provide a tube 1, preferably rectangular in cross-section, and being pierced with a series of aligned slots 2. Vanes 3 which are secured to shafts 11 and journaled to the tube 1, are extended through the slots 2 into the said tube 1 about two-thirds of their length. A case 4 which is somewhat shorter than the tube 1, is mounted over the extending portions of the vanes 3 and secured to the side 30 of the said tube 1. The case 4 has its ends 5 closed, while its vertical side 6 is pierced with a series of slots 7. A plate 8, pierced with slots 9, corresponding to the slots 7 in the side 6, is slidingly secured to the said

40 side 6 for a purpose to be later explained. The vanes 3 have their ends, which project into the tube 1, secured to a rod 10 by means of links 14. Coil springs 12 are secured to each end of the rod 10 and to the tube 1, and 45 control the angle of the vanes. A felt lining 13 is provided on the ends 5 and the upper and lower sides of the case 4.

In operation, the ventilator may be mounted in any desired place, wherever there is a current of air, as for instance in the window of a moving vehicle such as an automobile, as shown in Figure 4. The current of air enters the tube 1 and turns the vanes 3 into

the direction in which it is moving and thereby creates a suction, which draws the 55 foul air out of the interior of the object in which it is installed. The coil springs 12 are provided to prevent a strong current from folding the vanes 3 up against the slotted side of the tube 1 and thereby completely 60 close the slots 2. In the event the suction is too strong, it may be regulated by means of the sliding plate 8 which is adapted to be moved over the slots 7, thereby controlling 65 the suction.

As shown in Figure 5, the case 4 and plate 8 may be omitted and the control of the suction regulated by the wind. In a case where the ventilator is used in a building, the vanes 3 will readily reverse themselves when the 70 wind reverses itself.

The purpose of the slots 2 in the wall of the tube 1 is to protect the interior of the vehicle or building from sudden reversals of direction of the wind, since the air, in attempting to pass through the case 4, will be subjected to such a whirling motion as to have its force vitiated, thus nullifying the ill effects otherwise to be experienced.

While we have herein described a certain 80 specific manner and method of constructing and assembling the elements of our invention, it is understood that we may vary from the same in minor details, not departing from the spirit of our invention, so as best 85 to construct a practical device for the purpose intended, as defined in the appended claims.

We claim:

1. In a ventilator for vehicles and buildings, comprising a tube having a series of vanes journaled therein, the combination comprising the inner wall of said tube having a plurality of slots, each of said vanes being adapted to have a portion thereof extended through one of the said slots, a case positioned on said inner wall, so as to form an enclosure therebetween, said case having apertures communicating said enclosure with the interior of the vehicle or building, and means for closing said apertures. 90

2. In a ventilator for vehicles and buildings, the combination, with a tube having a series of vanes journaled therein, and means for maintaining said vanes parallel with one 95 another, of means for vitiating the force of

back draft in said ventilator, said means comprising the inner wall of said tube having a plurality of slots, each of said vanes being adapted to have a portion thereof ~~ext~~
5 extended through one of said slots, a case positioned on said inner wall so as to form an enclosure thereinbetween, said case having

apertures communicating said enclosure with the interior of said vehicle or building.

In testimony whereof we affix our signatures.

ARCHIBALD N. LONGFIELD
BERTHA I. LONGFIELD.
